L. L. DODSON

RADIATOR CAP

Filed June 17, 1927

Inventor
Lewis L. Dodson

By Clarence A. O'Brien
Attorney

UNITED STATES PATENT OFFICE.

LEWIS L. DODSON, OF GREENWICH, OHIO.

RADIATOR CAP.

Application filed June 17, 1927. Serial No. 199,531.

My invention relates to radiator caps and has for an object to provide a fastening means for the cap whereby to firmly secure the same in position and permitting the instant releasing of the same whenever the cap is desired to be opened.

A further object of the invention is to provide a device of this character of simple construction, neat and attractive in appearance, adapted to positively secure the parts in locked position and which may be easily and quickly installed on practically any type of radiator filling openings.

Other objects and advantages reside in the special construction, combination, and arrangement of the various elements forming the invention as more fully hereinafter described and claimed, reference being had to the accompanying drawing forming part 20 hereof, wherein:

Figure 1 is an elevational view with parts broken away to show the manner of mounting the cap, and

Figure 2 is a fragmentary perspective view 25 showing the locking latch in disengaged position permitting the opening of the cap.

Referring now to the drawing I have shown my invention comprising a lower cap section comprising a collar 5 having an externally threaded boss 6 depending therefrom and adapted to be threadedly inserted in the neck 7 of the radiator filler opening. Extending from opposite sides of the collar is formed a pair of arms 8 arranged in a substantially horizontal position and having their outer ends provided with vertically extending slots 9 each pair of arms having a pin 10 arranged therebetween transversely of the slot. An upper section is adapted to 30 be mounted upon the lower section in superimposed relation and comprises a cap 11 for mounting over the opening in the collar 5 and provided with similarly arranged arms 12 arranged above the arms 8 of the lower

45 section. Vertically formed slots 13 are also arranged in the arms 12 having pins 14 extending transversely therethrough and mounted upon said pins within said slots are latches 15, said latches being rotatably carried on the pins so as to permit the free

movement thereof and near their free ends are formed slots 16 arranged transversely with respect to the latch and adapted to receive the pins 10 carried on the lower arms 8.

In this manner it is obvious that upon the engagement of the pin 10 by the slot 16 in the latch 15 that the upper and lower sections of the radiator cap may be firmly secured to each other.

A bolt 17 extends downwardly from the lower end of the latch upon which may be carried an ornamental object such as a ball made of onyx, glass, metal or other suitable material, and retained thereon by a nut 19. At the upper edge of the collar 5 of the lower section is formed an upwardly extending flange 20 over which is adapted to be carried a downwardly extending flange 21 formed on the under side of the cap 11 of the upper section. The edge of the flange 21 may 70 rest upon a rubber washer 22 arranged about the flange 20 so as to form a tight seal between the parts.

The ends of each pair of arms may be provided with a latch connecting means as heretofore described so that the upper section of the cap may be removed by releasing either side thereof. It is to be understood, however, that if desired the arms at one side of the cap may be provided with a permanently 80 formed pivotal connection so as to prevent the upper and lower sections from becoming entirely separated.

An ornamental device indicated at 23 may be mounted upon the upper portion of the cap 11 such as for instance, a motor meter or the like.

It is to be understood that my invention is not limited to the specific construction herein disclosed as various changes and modifications may be made therein without departing from the spirit of the invention or the scope of the appended claim.

I claim:

A radiator filler cap comprising a pair of cap sections detachably arranged in superimposed relation, means carried by the lower section whereby to secure the same to a radiator filler, arms extending in spaced parallel relation at opposite sides from each of said 100

sections, latches pivotally mounted to the arms of said upper section and having slots formed therein, a pin carried by the arms of said lower section and adapted to be inserted in said slot, whereby to releasably secure the latches to the lower arms at each side of the cap and permitting selective disengagement

of either of said latches for opening movement of the uppermost sections from either side of the cap, the free ends of the latches being reduced and adapted to removably support an ornamental object thereon.

In testimony whereof I affix my signature.

LEWIS L. DODSON.
